(57) **CLAIM**

The ornamental design for a belt, as shown and described.

DESCRIPTION

FIG. 1 is a front left perspective view of a belt showing my design;

FIG. 2 is a left side view thereof;

FIG. 3 is a front view thereof;

FIG. 4 is a right side view thereof;

FIG. 5 is a top view thereof;

FIG. 6 is a bottom view thereof;

FIG. 7 is a front left perspective view of a second embodiment of my belt design;

FIG. 8 is a left side view thereof;

FIG. 9 is a front view thereof;

FIG. 10 is a right side view thereof;

FIG. 11 is a top view thereof; and,

FIG. 12 is a bottom view thereof.

The broken lines in FIGS. 1 through 12 depict portions of the article that form no part of the claimed design.

The break lines shown in FIGS. 1-4 and 7-10 symbolize breaks in the length of the article in which the claimed design is embodied. The appearance of any portion of the article between the break lines forms no part of the claimed design.
